UNITED STATES PATENT OFFICE.

CONSTANTINE G. MILLER, OF CHICAGO, ILLINOIS, ASSIGNOR TO THE MEAKER COMPANY, A CORPORATION OF ILLINOIS.

ELECTROPLATING APPARATUS.

Application filed June 2, 1924. Serial No. 717,456.

This invention relates to electroplating and cleaning apparatus suitable for cleaning and subsequently electroplating metallic articles.

In such apparatus it is customary to use a series of tanks for cleaning, rinsing, electroplating, rinsing and so forth. Heretofore the transferring of the articles to be plated from one tank to the next has involved a great amount of labor.

One of the principal objects, therefore, of the present invention is to provide an electroplating apparatus in which the articles are moved through each tank and then transferred to the next tank automatically and without hand labor.

Other and further important objects of this invention will be apparent from the disclosures in the accompanying drawings and the following specification.

The invention (in a preferred form) is illustrated on the drawings and hereinafter more fully described.

On the drawings:—

Figure 1 is a side elevation of the entire apparatus.

Figure 2 is a plan view of one portion thereof.

Figure 3 is an end view of the same.

Figure 4 is a longitudinal vertical central section through a portion of the apparatus.

Figure 5 is a side elevation of an enlarged scale of one end of the apparatus.

Figure 6 is a side elevation of one of the hanger supports and contact shoes and chain connected thereto.

Figure 7 is a section on the line 7—7 of Figure 6.

Figure 8 is a side elevation of one of the conveyor chains and hanger supporting links carried thereby.

Figure 9 is a front view of the same.

Figure 10 is a side elevation of the same parts at their upper point of travel.

Figure 11 is a side elevation of one part of the driving mechanism.

Figure 12 is a plan view of the same.

As shown on the drawings:—

The apparatus comprises a series of tanks, conveniently constructed of wood, arranged in a row which may be designated as cleaning tank 15, light acid dip tank 16, cold water rinse tank 17, electro-strike tank 18, cold water rinse tank 19, electro-plating tank

20, cold water rinse tank 21, and hot water rinse tank 22.

These tanks are supported by channel beams 23, the ends of which are supported by the side girders 24 of the framework of the apparatus. This framework is of usual construction so need not be described in detail.

An endless chain 25 passes along each side of the row of tanks slightly above their upper margin. This chain is supported by sprockets 26 carried by the framework and a device 27 for taking up any slack in the chain.

At intervals along this chain are pivotally connected a series of shoes 28, which, as the chain is travelling along the lower portion of its course ride along a pair of bus-bars 29 and make electrical contact therewith.

These shoes also serve the purpose of supports for the ends of bars 30 forming part of the hangers from which the articles to be plated are suspended. For this purpose ribs 34 are provided on the inner face of the shoes to form a notch for the reception of the bars 30. Depending from these bars 30 are a series of rods 31 having cross pieces 32 secured thereto, the latter having bent ends to ensure engagement with the articles 33 to be plated.

The chain 25 serves to move the hangers through the tanks but means must also be provided for lifting the hangers out of one tank and dropping them into the next. For this purpose a series of vertically arranged conveyor chains 35 are provided passing around sprockets 36. The conveyor chains 35 are arranged inside the chains 25 and adjacent the ends of each pair of tanks so that they can lift the hangers off the shoes 28 when the latter approach the end of one tank, move them forward and drop them onto another shoe at the beginning of the next tank and so on.

For engaging the hangers the device shown more particularly in Figures 8, 9 and 10 may conveniently be employed. This device comprises two links 37—37 each pivotally connected at one end to the chain 35. The free ends of the links 37—37 are connected together by a third link 38 of curved or arcuate form. Gravity causes the links on their upward movement to assume the position shown in full lines in Figure 8. When the chain reaches the top of its path

of movement the parts take the position shown in Figure 10. Then on the downward movement the link 37 which on the upward path was lying parallel to the chain moves outwardly while the other link swings inwardly. In this way the link 38 is always maintained in a substantially horizontal position so that the ends of the bars 30 may be supported thereby during the upward, 10 transverse and downward movement of the chain.

As the links, as shown in Figure 9, are arranged to one side of the chain, a lug 39 is formed on each link 37, which lug extends 15 across the chain and is provided with a set-screw 40 by which the range of movement of the link relatively to the chain may be adjusted.

The chains 25 and 35 are operated in synchronism so that as the links 37, 38 move upwardly or downwardly towards the chain 25 they meet one or other of the shoes on the latter. For this purpose the driving mechanism shown in Figures 5 and 11 is provided. This comprises a sprocket wheel 41 on a shaft 42 on which is mounted a gear 43 meshing with a gear 44 on the shaft 45. On this shaft 45 is another sprocket wheel 46 which drives a chain 47 passing around a sprocket wheel 48 on a shaft 49. The latter not only carries one of the sprockets 36 but also another sprocket (not shown) for a chain 49^a by means of which the adjacent conveyor chain 35 and its associated parts are driven.

While the vertically arranged conveyor chains 35 receive their driving power from the chain 25, the latter is driven from a shaft 50 which carries a worm wheel 51. 40 This worm wheel is in turn driven by a worm 52 on a shaft 53 carrying a sprocket 54 connected by a chain 55 to a sprocket 56 on a shaft 57. This shaft 57 carries a second sprocket 58 driven by a chain 59 passing round a sprocket 60 on a shaft 61 driven by a motor 62.

Extending longitudinally across the electro-strike tank 18 and the electro-plating tank 20 are a series of bars 63 connected at 50 their ends to bus bars 64 to which current is supplied by bar 65. From these bars are suspended anodes 66 of the metal to be deposited.

The solutions employed in the cleaning tank 15, light acid dip tank 16, electro-strike tank 18 and electro-plating tank 20 will be selected to suit the character of work to be done, the condition of the articles as they reach the apparatus, the metal to be deposited and so forth.

The number of tanks used may be varied as in some cases it may be possible to dispense with some of those shown in the present case. It will also be evident that the time of treatment in each step of the process

may be varied by changing the length of the tanks.

In operation the hangers are transported continuously by the conveyor chains 25 and 35 and the articles to be plated are hung 70 on the hangers as the latter approach the tank 15 and removed therefrom as the hangers leave the tank 22.

I am aware that numerous details of construction may be varied through a wide 75 range without departing from the principles of this invention, and I therefore do not purpose limiting the patent granted otherwise than necessitated by the prior art.

I claim as my invention:—

1. An electroplating apparatus comprising a plurality of tanks, a hanger for supporting articles to be plated, a bus-bar parallel to the tanks, shoes adapted to slide along the bus-bar and also support one end 85 of said hanger, a conveyor for moving said shoes along said bus-bar and a second conveyor adapted to lift the hanger off its supporting shoe and out of the adjacent tank and drop it onto one of said shoes and into 90 the next tank.

2. An electroplating apparatus comprising a row of tanks, a hanger for supporting articles to be plated, an endless chain on each side of said row of tanks, hanger supporting members on said chain, further endless chains vertically arranged on each side of said row of tanks at the adjacent ends of two tanks, a pair of links pivotally connected to each of the second pair of chains and 100 a third curved link connecting the first two links, whereby the third link is maintained in hanger supporting position during the upward, horizontal and downward movement of the second pair of chains, and means for operating said sets of chains in synchronism whereby the links on the second pair of chains lift the hanger off its supporting members and out of the adjacent tank and dropping it onto said supporting 110 members and into the next tank.

3. An electroplating apparatus comprising a row of tanks, a hanger for supporting articles to be plated, a horizontal conveyor on each side of said row of tanks, endless chains vertically arranged on each side of said row of tanks at the adjacent ends of two tanks, a pair of links pivotally connected to each of said chains, and a third curved link connecting the first two links, 115 whereby the third link is maintained in hanger supporting position during the upward, horizontal and downward movement of the chains, and means for operating said conveyor and chains in synchronism whereby said links lift the hanger off said conveyor and out of the adjacent tank and drop it onto said conveyor and into the next tank.

4. An electroplating apparatus comprising a plurality of tanks, a hanger for sup-

porting articles to be plated, means for transporting the hanger downwardly, horizontally, upwardly, horizontally and downwardly, means for supplying current to the hanger during the first mentioned horizontal movement, and means for breaking the circuit adjacent the beginning of the upward movement and closing the circuit adjacent the end of the downward movement, thereby allowing the lower portion of the hanger to dip into said plurality of tanks successively and permit the passage of current therethrough only whilst the hanger is in its lowermost position.

In testimony whereof I have hereunto subscribed my name.

CONSTANTINE G. MILLER.
